CLAIBORNE W. GOOCH, OF DETROIT, MICHIGAN, ASSIGNOR TO BURROUGHS ADDING MACHINE COMPANY, OF DETROIT, MICHIGAN, A CORPORATION OF MICHIGAN.

ADDING-MACHINE.

1,327,320.

Specification of Letters Patent.

Patented Jan. 6, 1920.

Application filed February 15, 1916. Serial No. 78,392.

To all whom it may concern:

Be it known that I, CLAIBORNE W. Gooch, a citizen of the United States, residing at Detroit, in the county of Wayne and State 5 of Michigan, have invented new and useful Improvements in Adding-Machines, of which the following is a specification.

The present invention relates to the key-driven class of adding machines which do 10 not ordinarily have any printing equipment. It is frequently desirable in the carrying on of calculating work through use of machines of this sort, to be able to preserve a grand total of the sums of several series 15 of additions or computations. Ordinarily these machines have a single set of registering wheels and when so equipped there is no way of preserving a registration of a sum or total while another is being accumulated. 20 The purpose of my present invention is to enlarge the capacity of machines of this class by providing an additional set of accumulating wheels and so relating them to the key-driven actuating mechanism or to 25 the regular set of wheels, that the registration of a sum or total may be preserved upon this additional set of wheels while the regular set is returned to zero for the commencement of a new series of registering operations, 30 the sum total of which may be added to that preserved upon the additional set of wheels. In carrying out my invention I provide for using the machine in the ordinary way, as a single accumulator machine, 35 and I provide for bringing into play the additional set of wheels at the will of the operator in order that registrations may be made simultaneously upon the two sets of wheels, and I further provide for resetting the 40 regular set of wheels to zero without affecting the additional set of wheels. Provision is also made for simultaneously resetting both sets of wheels to zero.

In the construction here shown the additional set of wheels is located forward of the regular set of wheels and transmission gearing is employed between the two sets of wheels and a gang of clutches which may be opened and closed at will so that registration 45 may be effected upon the regular set of wheels only, or may be effected simultaneously upon the two sets of wheels. Zeroizing mechanism is provided for each set of wheels, that for the regular set of 50 wheels being actuated by the stroke of a

hand-lever, as usual, and that for the additional set of wheels being arranged to be coupled with and uncoupled from the zeroizing mechanism for the regular set of wheels. The opening of the aforesaid 60 clutches to disconnect the additional set of wheels from the regular set of wheels is accompanied by locking of the additional set of wheels against turning, and provision is made for unlocking those wheels as an 65 accompaniment to the coupling together of the two zeroizing mechanisms. Provision is furthermore made for opening the clutches as an incident to the coupling together of said mechanisms because, with the two sets 70 of wheels carrying different registrations, they should not of course be geared together when simultaneous zeroizing of them is to be practised.

In the drawings which accompany and 75 form part of this specification, Figure 1 represents the front portion of a machine of the class concerned, the same containing one form of embodiment of my present invention and the parts appearing in right-side elevation except that the inclosing casing is in 80 section and a supporting frame-piece is omitted and certain rods and shafts correspondingly appear in cross-section; Fig. 2 is a sectionalized plan view of the same portion of the machine, which is represented as laterally condensed; Fig. 3 is a top plan view embracing only a limited portion of what is illustrated in Fig. 2, the parts being 85 shown on an enlarged scale as compared therewith and under an adjustment which provides for simultaneous registration upon the two sets of wheels; Fig. 4 is a similar view illustrating a somewhat different condition, to wit, that brought about through 90 the setting of the special key which provides for simultaneous zeroizing of the two sets of wheels; Fig. 5 is a vertical section taken substantially on the line 5—5 of Fig. 2 and 95 illustrates parts at the left-hand side of the 100 machine set for simultaneous registration of amounts upon the two sets of wheels; Fig. 6 is a similar view illustrating the effect upon these parts of operating the aforesaid key which provides for simultaneous zeroizing of the two sets of wheels, while the other special key, which provides for simultaneous registration upon said wheels, remains down; Fig. 7 is a sectionalized view in side elevation of the duplex accumulating mech- 105 110

- anism shown upon a somewhat larger scale than in Fig. 1 and with various parts omitted and others broken away, the particular condition depicted being that under which the 5 regular set of wheels register zero, with the zeroizing hand-lever drawn forward, whereas the additional set of wheels is unaffected by the operation of said hand-lever and continues to register a total; Fig. 8 10 is a cross-section taken substantially on the line 8—8 of Fig. 2; Fig. 9 is a vertical cross-section taken substantially on the line 9—9 of Fig. 5; Fig. 10 is a vertical cross-section taken substantially on the line 10—10 of Fig. 15 5; Fig. 11 is a vertical cross-section taken substantially on the line 11—11 of Fig. 2.

So far as the machine proper is concerned, comprising the equipment of numbered keys and the levers upon which they act and the 20 means for measuring the extent of movement thereof and transmitting the movement to the regular set of adding wheels, no detailed description need be given because that is all disclosed in one or more prior 25 patents.

In the present drawings only the forward portions of the column actuators F' appear, as in Fig. 1, and the stems of a few of the numbered keys F which drive said actuators, appear in horizontal section in Fig. 2. The reference letter A designates the numeral wheels composing the regular set, the same being located as usual within the forward part of the inclosing casing Z to be 30 read through eight openings z in the top of said casing. The reference A' designates the gear wheels arranged as usual immediately adjacent the said numeral wheels and being the elements of the regular accumulating 35 mechanism which directly receive measured movements in clockwise direction as the same are transmitted from the column-actuators through the medium of operating connections identical with those illustrated and 40 described in the aforesaid patent.

In carrying out the present invention the second set of wheels A' is located within the casing forward of the regular set of numeral wheels, the casing being extended sufficiently for the purpose and provided with a set of eight openings z' through which to 50 read this additional set of wheels. Planetary gearing of the same sort as that associated with the regular numeral wheels, is 55 employed in connection with the extra set of wheels, and this gearing is controlled and operated for purposes of transmitting carrying impulses from wheel to wheel of the extra set, by mechanism substantially duplicating that employed in connection with the 60 regular set of wheels. The gear wheels immediately adjacent the respective numeral wheels A', and corresponding with the before-identified gear wheels A', are designated 65 by the numeral 25. They are of somewhat

smaller diameter than the gear wheels A', owing to the character of the transmission gearing, presently to be described, which intervenes between the latter and said gear wheels 25, and the planet pinions D', carried 70 by the latter, are laterally displaced as compared with the regular planet pinions D,asmuch as the gear wheels 25 are not of such diameter as to permit of said planet pinions D' being accommodated between the 75 peripheral portions of these gear wheels and the sun gears E'. This slight difference will be readily discerned upon comparison of Figs. 8 and 11.

Upon a rod 26 extending through the 80 framework of the machine midway between the two sets of numeral wheels, gear wheels 27 are journaled, said gear wheels being constantly in mesh with the gear wheels A' respectively. Immediately adjacent these gear 85 wheels 27 to the left thereof, gear wheels 28 of smaller diameter are journaled upon said rod as best shown in Fig. 10, and these latter gear wheels are constantly in mesh with the gear wheels 25 respectively. Obviously if 90 the gear wheels 27 and 28 are rotatively connected together, any movement imparted to the gear wheels A' will be transmitted to the gear wheels 25.

Provision is made for rotatively connecting and disconnecting gear wheels 27 and 28 at will as follows: The web of each gear wheel 27 around the hub has a circular series of clutch holes 27^a, and a sliding clutch pin 29 occupies an opening in the web of the 95 adjacent gear wheel 28 and may enter any one of the said holes 27^a. This clutch pin is carried upon a sleeve 30 which is mounted to slide upon the elongated hub of the gear wheel 28 (Fig. 10). A yoke 31 supported 100 upon a shaft 32 has an extended left side arm forked to straddle the sleeve 30 and engage the circumferential groove therein. The shaft 32 is laterally shiftable for projecting the clutch pin 29 into any one of the 105 clutch holes 27^a and withdrawing it therefrom. There is of course a series of these 110 yokes, as illustrated in Fig. 2, one for each of the clutch sleeves, and they are suitably confined upon the shaft 32 against lateral 115 movement relative thereto.

Shifting of the said shaft 32 of course shifts all of the yokes and the clutch sleeves so as to simultaneously connect or disconnect the gear wheels 27 and 28 of the several 120 pairs and thereby bring into action or throw out of action the numeral wheels of the forward or extra set. I provide a depressible key 33 for shifting said shaft, this key being preferably located at the left of the keyboard of the machine. The stem 33^a of said key is preferably notched as at 33^b for engagement with the keyboard plate Z', as shown in Figs. 5 and 6, to keep the key depressed in opposition to the spring 34 which 125 130

normally holds it up. The operating connections between said key and the laterally shiftable shaft 32 are of the following description: A stud 33^e on the key stem engages 5 a slot in the rear end of a bell crank lever 35 and the depending branch of the latter has a stud 35^a occupying a slot in the rear portion of a bar 36. The rear portion (Fig. 2) of this bar stands on edge vertically 10 whereas the laterally and thence forwardly extending portion of the bar lies horizontally, the same having an obliquely extending terminal portion pivotally united with one arm of a bell crank lever 37 the other arm of which embraces a collar 32^a on 15 the shaft 32. Obviously depression of the key 33 will operate to thrust forward the bar 36 and shift the shaft 32 to the right, and this will in turn clutch together the wheels 20 27 and 28 of the respective bars. Upon release of the key the spring 34 will obviously function to unclutch said gear wheels.

Manifestly with the said gear wheels clutched together simultaneous registration 25 of amounts upon both sets of numeral wheels will result from operating the numbered keys of the machine. Thus both sets of wheels may be caused to accumulate the same total. Then by release of the special 30 key 33 the rear or regular set of wheels will be disconnected from the front or extra set of wheels, and may then be independently zeroized in preparation for accumulating a new series of amounts. By again setting down the key 33 that new series of amounts 35 will be simultaneously accumulated in the forward set of wheels and added to the previous total reserved upon that set of wheels. Thus a succession of totals of different series 40 of amounts may be separately accumulated upon the regular set of wheels, and a grand total registered upon the forward set of wheels. Of course it will be obvious that where the work in hand calls for but a single accumulator, the special key will not 45 be used and the machine will serve in just the same way as the ordinary single accumulator machine.

The arrangement for turning the regular 50 set of wheels to zero includes a rock shaft S rotated anti-clockwise by forward pull of the hand lever W (Fig. 2), and carrying a crank plate 11 having a stud 12 in a cam slot of a lever 13. The latter is forked to engage a stud on a crank arm 10^a of a rock shaft 10 having flattened sections to operate upon 55 backstop pawls R, disengaging them from ratchet wheels E² and causing them to disengage driving pawls 9 from said ratchet. The rocking of shaft 10 (through its cam-arm 10^b) also shifts journal rod 19, to laterally displace overthrow preventing 60 toothed disks 16, further freeing the gears for backward turning. Springs J so turn 65 the gears and numeral wheels through the

medium of segments H and their connections the details of which are shown and described in the Horton Patent No. 1,243,839 issued October 23, 1917. To cause said segments to so operate the gear disks are locked 70 by hooked levers 2 thrown into the paths of studs E on said disks by a bail cross-rod 6 occupying cam-slots of the levers 2, one side of the bail being part of the aforesaid crank-plate 11. Said cross-rod also occupies 75 cam-slots of stop levers 4 having hooks 4^a to intercept lugs d on the respective numeral wheels for preventing their backward turning beyond the zero position.

Provision is made for zeroizing the forward set of wheels in the same way that the rear set is zeroized, that is to say, by backward rotation under action of the carrying springs J^x. As before stated the carrying mechanism of the extra accumulator is identical with that of the regular accumulator. I may here add that the devices for acting upon the gear disks C^x in a zeroizing operation, and for stopping the wheels A^x at zero, are identical with those performing similar 80 functions in connection with the rear set of wheels A, and I have applied the same numerals to corresponding parts associated with the forward set of wheels using the suffix "x" as in the case of other reference 85 characters already employed in this specification. There is no occasion, however, for employing in connection with the forward set of wheels the devices hereinbefore referred to which require disablement as a 90 preliminary to zeroizing the rear set of wheels and no such devices or disabling mechanism appear in connection with the forward set of wheels. It will be understood that those devices, as directly associated 95 with the rear set of wheels, exercise control also over the forward set of wheels, inasmuch as the latter are driven for registration purposes only through the transmission gearing which connects them with the regular set of wheels. When disconnected from the latter and so no longer under the control of said devices, it is desirable that the forward set of wheels shall be locked against 100 any accidental turning and this I provide 105 for by equipping the clutch sleeves 30 with locking pins or studs 40 to engage holes in plates 41 surrounding the rod 26. Each of these plates has a circular series of holes 41^a corresponding in number with the clutch 110 holes 27^a in the gear wheels 27 so that to whatever position the associated clutch sleeve 30 may have been turned, its locking stud 40 will enter one of the holes 41^a when the shaft 32 is shifted to the left. Obviously 115 the numeral wheels A^x will thereby be locked 120 against rotation.

The zeroizing mechanism for the forward set of wheels includes a rock shaft S^x corresponding with the rock shaft S, and I pro- 130

vide for operatively connecting these two rock shafts together so that the forward set of wheels may be zeroized by the act of pulling forward the hand lever W, and I also 5 provide for the unlocking of the forward set of wheels as an incident to the coupling together of said rock shafts. For the purposes of this coupling together of the rock shafts the before-mentioned crank-arm 11, 10 secured to the left-hand end of the rock shaft S, has formed integrally with it an upwardly extending arm 11^a carrying a stud 11^b. Similarly the left-hand bail side-arm 5^x of the forward zeroizing mechanism has 15 formed integrally with it an upwardly extending arm 42. A link 43 is pivotally connected to the upper end of said arm 42 and extends rearwardly adjacent the arm 11^a where it is formed with a notch 43^a to engage the stud 11^b. The normal condition is 20 illustrated by dotted lines in Fig. 1 and the same condition is illustrated in Fig. 5. The forward side of the notch is above the stud so that rocking of the shaft S does not affect the shaft S^x. Lowering of the link 43 engages the notch with the stud as shown in Fig. 6 and under these conditions the rocking of the shaft S is accompanied by a rocking of the shaft S^x. 25 The lowering of the said link 43 is accomplished by depression of a special key 44 which is located at the left of the keyboard forward of the key 33. The stem 44^a of this key carries a stud 44^b which occupies an arc-shaped slot 43^b in the rear end of the link 43. Said key is normally upheld by a spring 45 and upholds the said link, but obviously when the key is depressed the link will be forced down and the connection established 30 between the rock shaft S^x and the regular shaft S, as illustrated in Fig. 6. The depression of this key also unlocks the forward wheels, this being effected by shifting the lock plates 41 to the left through the medium 35 of connections I shall next describe.

The before-mentioned key stud 44^b is extended to the left, as best shown in Fig. 9, and occupies a cam slot 46^a in the lower arm of a lever 46 which is pivoted upon a frame 40 stud 48. The upper arm of this lever is pivotally connected to a bar 49 of a character similar to the before-described bar 36. Thus the rear portion of this bar 49 is set 45 on end vertically and its forward portion lies horizontally. This forward portion is pivotally connected with one arm of a bell-crank lever 50 (Fig. 2), the other arm of which embraces a collar 51^a on a laterally shiftable rod or shaft 51. The aforesaid 50 lock-plates 41 constitute extensions of the side arms of a series of yokes 41^b which are mounted upon said shaft 51, suitably confined thereon against any relative lateral movement. Depression of the key 44 rocks 55 the lever 46 from the position shown in Fig.

5 to that shown in Fig. 6, and therefore thrusts the link 49 forward and shifts the shaft 51 to the left. The lock-plates 41 are free to slide upon the rod 26 and the said shifting of the shaft 51 shifts the lock-plates 70 disengaging them from the several lock-studs 40, thereby freeing the forward wheels for backward rotation. For the purpose of additionally supporting and steadyng the lock-plates I prefer to provide them with 75 downward extensions slotted to embrace a cross rod 52, as illustrated in Figs. 5 and 6. Manifestly no attempt should be made to simultaneously zeroize the two sets of wheels when they are geared together, for after the 80 first series of amounts have been simultaneously registered upon the two sets of wheels and the regular set has been zeroized, the two sets of wheels will not register the same thing and if geared together both sets 85 could not be simultaneously brought to zero. Of course if the key 33 is up no such thing has to be taken into account, but that key may be down at the time the zeroizing key 44 is depressed. Hence I provide for disconnecting the two sets of wheels by the pull 90 on the hand lever W at the outset of a zeroizing operation, in case the key 33 happens to be down. To this end the bar 36 is slotted, as before mentioned, to receive the stud 95 35^a. A spring 53 connects that stud with a stud at the rear end of said bar 36 so as to provide a yielding connection between the bell-crank lever 35 and the bar and therefore 100 make it possible to operate the bar independently of the key 33, forcing it rearward to open the clutches and disconnect the two sets of wheels. On the cross rod 14 which supports the gear sectors E' I journal an arm 60 which extends forward of a shoulder 36^c (Fig. 2) of the bar 36. Said arm is widened at its middle portion and the forward edge 60^a has a cam relationship with the before-mentioned roller 12. If the key 105 33 is down as shown in Fig. 6 the forward thrust of the bar 36 will have swung the arm 60 forward to the position shown in full lines. Then when the shaft S is rocked at the outset of a zeroizing operation the roller 12 will force said arm 60 rearward 110 and thereby force the bar 36 rearward so that the wheels will be disconnected just as though the key 33 had been released. The upper half of the forward edge 60^a of the arm 60 is concentric with the shaft S as the 115 zeroizing operation continues so that the stud 12 will then traverse said edge idly.

I claim:

1. The combination of vibrating register actuators; keys for differentially driving 125 said actuators; a set of adding wheels driven by said actuators; a second set of adding wheels; transmission gearing between the two sets of adding wheels; clutches in said transmission gearing; means for operating 130

- the clutches to cause simultaneous registration upon said sets of wheels or registration only upon the first-mentioned set, each set of wheels having its own carrying mechanism; zeroizing mechanism for each set of wheels; and a single means for simultaneously actuating said mechanisms, or separately actuating that pertaining to the first-mentioned set of wheels.
- 10 2. The combination of vibrating register actuators; keys for differentially driving said actuators; a set of adding wheels driven by said actuators; a second set of adding wheels; transmission gearing between the 15 two sets of adding wheels; clutches in said transmission gearing; means for operating the clutches to cause simultaneous registration upon said sets of wheels or registration only upon the first-mentioned set, each set 20 of wheels having its own carrying mechanism; zeroizing mechanism for each set of wheels; and a single means for simultaneously actuating said mechanisms, or separately actuating that pertaining to the first-mentioned set of wheels; together with means for opening the aforesaid clutches so that when simultaneously zeroized the sets of wheels will turn independently of each other.
- 25 3. The combination of vibrating register actuators; keys for differentially driving said actuators; a set of adding wheels driven by said actuators; a second set of adding wheels; transmission gearing between the 30 two sets of adding wheels; clutches in said transmission gearing; and means for operating the clutches to cause simultaneous registration upon said sets of wheels or registration only upon the first-mentioned set, each set 35 of wheels having its own carrying mechanism; together with means for locking the wheels of the second set when unclutched from the wheels of the first set.
- 40 4. The combination of vibrating register actuators; keys for differentially driving said actuators; a set of adding wheels driven by said actuators; a second set of adding wheels; transmission gearing between the two sets of adding wheels; clutches in said 45 transmission gearing; means for operating the clutches to cause simultaneous registration upon said sets of wheels or registration only upon the first-mentioned set, each set of wheels having its own carrying mechanism; together with means for locking the wheels of the second set when unclutched from the wheels of the first set; zeroizing mechanism for each set of wheels; means for simultaneously actuating said mechanisms, or separately actuating that pertaining to the first-mentioned set of wheels; and means for unlocking the wheels of the second set as an incident to zeroizing them.
- 50 5. The combination of vibrating register actuators; keys for differentially driving said actuators; two accumulators each comprising axially alined numeral wheels and gear wheels associated therewith respectively; transmission gears arranged in pairs meshing respectively with gears of the two accumulators; a gang of clutch sleeves carried by corresponding gears of said pairs and shiftable axially thereof to connect and disconnect the same and the other members of the respective pairs; and a key and connections for operating said sleeves.
- 55 6. The combination of vibrating register actuators; keys for differentially driving said actuators; two accumulators each comprising axially alined numeral wheels and gear wheels associated therewith respectively; transmission gears arranged in pairs meshing respectively with gears of the two accumulators; a gang of clutch sleeves carried by corresponding gears of said pairs and shiftable axially thereof to connect and disconnect the same and the other members of the respective pairs; a key and connections for operating said sleeves; lock plates with which said sleeves engage when shifted to disconnect the transmission gears; zeroizing mechanism; a key and connections for rendering the same operative as to the accumulator locked by said plates; and means operated by last-mentioned key for shifting said lock plates to unlock said accumulator.
- 60 7. The combination of vibrating register actuators; keys for differentially driving said actuators; two accumulators each comprising axially alined numeral wheels and gear wheels associated therewith respectively; transmission gears arranged in pairs meshing respectively with gears of the two accumulators; a gang of clutch sleeves carried by corresponding gears of said pairs and shiftable axially thereof to connect and disconnect the same and other members of the 130

respective pairs; a key and connections for operating said sleeves; zeroizing mechanisms for the accumulators respectively, said mechanisms being normally disconnected from each other; a key and connections for operatively coupling said mechanisms together; and means for actuating said mechanisms, with provisions for shifting the clutch sleeves to disconnect the transmission gears independently of the first-mentioned key and connections.

9. The combination of vibrating register actuators; keys for differentially driving said actuators; two accumulators each comprising axially alined numeral wheels and gear wheels associated therewith respectively; transmission gears arranged in pairs meshing respectively with gears of the two accumulators; a gang of clutch sleeves carried by corresponding gears of said pairs and shiftable axially thereof to connect and disconnect the same and the other members of the respective pairs; a key and connections for operating said sleeves; lock plates with which said sleeves engage when shifted to disconnect the transmission gears; zeroizing mechanisms for the accumulators respectively, said mechanisms being normally disconnected from each other; a key and connections for operatively coupling said mechanisms together; means operated by the last-mentioned key for shifting said lock plates; and means for actuating said mechanisms, with provisions for shifting the clutch sleeves to disconnect the transmission gears independently of the first-mentioned key and connections.

10. The combination of vibrating register actuators; keys for differentially driving said actuators; two accumulators each comprising axially alined numeral wheels and gear wheels associated therewith respectively; transmission gears arranged in pairs meshing respectively with gears of the two accumulators; a gang of clutch sleeves carried by corresponding gears of said pairs

and shiftable axially thereof to connect and disconnect the same and other members of the respective pairs; a key and connections for operating said sleeves including a bar and a spring between it and the key; zeroizing mechanisms for the accumulators respectively, said mechanisms being normally disconnected from each other; a key and connections for operatively coupling said mechanisms together; means for actuating said mechanisms, including a rock shaft; an arm on said shaft; and a lever operated by said arm and operating upon the aforesaid bar.

11. The combination of vibrating register actuators; keys for differentially driving said actuators; two accumulators each comprising axially alined numeral wheels and gear wheels associated therewith respectively; transmission gears arranged in pairs meshing respectively with gears of the two accumulators; a gang of clutch sleeves carried by corresponding gears of said pairs and shiftable axially thereof to connect and disconnect the same and the other members of the respective pairs; a key and connections for operating said sleeves including a bar and a spring between it and the key; lock plates with which said sleeves engage when shifted to disconnect the transmission gears; zeroizing mechanisms for the accumulators respectively, said mechanisms being normally disconnected from each other; a key and connections for operatively coupling said mechanisms together; means operated by the last-mentioned key for shifting said lock plates; means for actuating said mechanisms, including a rock shaft; an arm on said shaft; and a lever operated by said arm and operating upon the aforesaid bar.
